(57) CLAIM

The ornamental design for barbecue lid, as shown and described.

DESCRIPTION

FIG. 1 is an isometric view of a barbecue lid showing the new design;

FIG. 2 is a front view of the barbecue lid of FIG. 1;

FIG. 3 is a side view of the barbecue lid of FIG. 1; and,

FIG. 4 is a top view of the barbecue lid of FIG. 1.

The design is shown in solid lines in the drawings. Any broken lines in the drawings are for illustrative purposes only and form no part of the design.
